UNITED STATES PATENT OFFICE.

THOMAS W. BROWN AND HARRY N. STAMOS, OF CENTERVILLE, IOWA.

RAILWAY-SWITCH-POINT PROTECTOR.

Application filed February 18, 1926. Serial No. 89,103.

Our invention relates to improvements in railway switch point protectors, and among the objects of the invention are to avoid wearing the terminals of switch rails to a knife edge by laterally shifting the wheels of a train so that the wheel flanges will contact the switch rail at a point back from the entry edge of said rail where its cross section is of such thickness as to better resist the wear incident to the repeated impact of said wheel flanges in traffic; to prevent "split switch wrecks"; and to provide a guard plate which may be readily adjusted to rails of different height and which is reversible so that when worn along one longitudinal margin it may be turned over to present the other margin and thereby greatly prolong the life of said guard plate.

In order that the invention may be fully understood, reference will now be had to the accompanying drawing, in which:—

Fig. 1 is a broken elevation of a rail equipped with the guard plate.

Fig. 2 is a plan view of the parts disclosed by Fig. 1.

Fig. 3 is an end elevation of the parts disclosed by Fig. 2.

Fig. 4 is a detail perspective view of a filler block employed in carrying out the invention.

Referring now in detail to the different parts, A designates a railway rail, and B a switch rail of standard type.

2 designates the guard plate which comprises a pair of reversible sections 4 and 6 having abutting inclined edges with interlocking notches or serrations 8 and 10, respectively, to prevent accidental longitudinal shifting of the uppermost section upon the lowermost section. The uppermost section 4 is also held from accidental lateral displacement upon the lowermost section 6 by means of a longitudinal tongue 12 which fits into a complementary groove 14 in the lowermost section. The ends of the sections 4 and 6 are rounded or chamfered, as indicated at 16 to receive the impact of the wheel flange C and shift the same laterally away from the inner side of the rail head D, as shown by Fig. 3, so that said flange C will not strike the end of the switch rail B. The sections 4 and 6 have inwardly projecting longitudinal flanges 20 so that the flange of

the section which happens to be uppermost will fit snugly against the under surface ^d 55 of the rail head D.

22 designates a filler block of metal or other suitable material adapted to fill the space between the lowermost flange 20 and the rail A, and also to assist in supporting ⁶⁰ the lowermost section 6 of the guard plate 2. Said filler block 22 has upwardly projecting lugs 24 adapted to fit in complementary recesses 26 of the flanges 20 and thereby prevent longitudinal displacement ⁶⁵ of said filler block 22.

The guard plate 2 is firmly held in position against the adjacent side of the rail A and the filler block 22 by a bracket 28 consisting of a horizontal arm 30 and a vertical arm 32. The horizontal arm 30 extends beneath the base of the rail A and has an upwardly and inwardly curved terminal 34 spaced from the rail base to receive a tapered key 36, which is driven between the adjacent ⁷⁰ margin of the rail base and said curved terminal 34 to cause the vertical arm 32 to firmly force the guard plate 2 against the adjacent margin of the rail base which secures said key from vertical displacement ⁷⁵ and said key is held from longitudinal displacement after being driven inwardly between the rail base and the terminal 34 by a cotter 40, which is placed through an opening in the key and bears against the ⁸⁰ rear side of the upturned terminal 34.

The sections 4 and 6 of the guard plate 2 have cavities 42 and 44, respectively, so that the one which happens to be lowermost may receive a lug 46 projecting inwardly ⁸⁵ from the vertical arm 32 of the bracket 28 and thereby secure the guard plate 2 from longitudinal displacement.

With the parts constructed and arranged as shown and described, it is apparent that ⁹⁰ whichever section of the guard plate 2 happens to be uppermost, said section may be adjusted longitudinally upon the lowermost section as shown by dotted lines Fig. 1, to accommodate rails of different heights. It ¹⁰⁰ is also apparent that when the uppermost section becomes worn by the wheel flanges C that the guard plate 2 can be reversed or turned upside down to bring the unworn section uppermost, thereby prolonging the usefulness of said guard plate 2.

In some instances the number of parts can be reduced by forming the filler block 22 integral with the section 6, in which case all wear from the wheel flanges C will come 5 upon the section 4, which can, when worn out, be replaced with another section of like construction.

From the foregoing description it is apparent that we have provided a device embodying the advantages above pointed out, and while we have shown and described a preferred construction, combination and arrangement of parts, we reserve all rights to such modifications thereof as properly fall 15 within the spirit and scope of the invention as claimed.

Having thus described our invention, what we claim and desire to secure by Letters Patent, is:—

- 20 1. A device of the class described consisting of a guard plate comprising two sections having abutting edges with interlocking notches, and means for securing said guard plate to one side of a rail.
- 25 2. A device of the class described consisting of a guard plate comprising two sections having abutting tongue and groove edges, and means for securing said guard plate to one side of a rail.
- 30 3. A device of the class described consisting of a guard plate comprising upper and lower sections with inclined abutting edges to permit vertical and longitudinal adjustment of the upper section upon the lower section.
- 35 4. A device of the class described consisting of a guard plate adapted to fit against one side of a rail, a bracket having a vertical arm for holding said guard plate 40 against the rail and a longitudinal arm to

extend beneath the rail, and a key for holding said bracket in place.

5. A device of the class described consisting of a guard plate adapted to fit against one side of a rail, a bracket having an upwardly projecting arm for holding said guard plate against the rail and a horizontal arm for extending beneath the rail and terminating in an upwardly extending terminal, and a tapered key adapted to be driven 45 between said terminal and the adjacent side of the rail to secure said bracket in place.

6. A device of the class described consisting of a guard plate adapted to fit against one side of a rail, a bracket having an upwardly extending arm for holding said guard plate against the rail and a longitudinal arm to extend beneath the rail, and means for securing said bracket to the rail. 55

7. A device of the class described consisting of a guard plate adapted to fit against one side of a rail, a bracket having an upwardly extending arm for holding said guard plate against the rail and a longitudinal arm to extend beneath the rail means for securing said bracket to the rail, and means on the upwardly extending arm for interlocking with said guard plate. 65

8. A device of the class described consisting of a guard plate adapted to fit against one side of a rail and having a pair of inwardly projecting flanges spaced from the upper and lower margins of said plate, and a filler block adapted to fit between the lowermost flange and the upper adjacent portion of the rail base. 75

In testimony whereof we affix our signatures:

THOMAS W. BROWN.
HARRY N. STAMOS.
